UNITED STATES PATENT OFFICE.

JOEL R. HUTTON, OF TONY, MONTANA.

FENCE-MACHINE.

SPECIFICATION forming part of Letters Patent No. 783,866, dated February 28, 1905.

Application filed July 9, 1904. Serial No. 215,940.

To all whom it may concern:

Be it known that I, JOEL R. HUTTON, a citizen of the United States, residing at Tony, in the county of Carbon, State of Montana, 5 have invented certain new and useful Improvements in Fence-Machines; and I do hereby declare the following to be a full, clear, and exact description of the invention, such as will enable others skilled in the art to which it applies to make and use the same.

This invention relates to machines for building wire fences; and it has for its object to provide a machine which may be used in the building of that style of fence comprising pairs of wires between which are held palings, the wires of each pair being twisted first one way and then the other between the successive palings.

The object of the invention is to provide a machine which may be easily and quickly applied to the wires, which will be held against displacement from the wires during operation, and which may be operated easily.

An additional object of the invention is to provide a machine which may be adjusted to accommodate differently-spaced pairs of wires and which may be manufactured at a low cost.

In the drawings forming a portion of this specification, and in which like numerals of 30 reference indicate similar parts in the several views, Figure 1 is a perspective view showing a machine embodying the present invention. Fig. 2 is an elevation illustrating the use of the machine. Fig. 3 is a section 35 taken longitudinally through the main bar of the machine and illustrating the means for adjusting the machine for differently-spaced wires. Fig. 4 is a detail perspective view showing one of the pivoted blocks with the 40 means for holding a pair of wires in the slots thereof.

Referring now to the drawings, the present fence-machine comprises a main bar 5, having at its central portion a handle 6, that projects at right angles therefrom, and at each side of which handle there is formed through the bar a longitudinal slot 7. In connection with the main bar 5 there are employed two L-shaped bars 8 and 9, which are disposed 45 against one side of the main bar 5 and at op-

posite sides of the handle 6. Through each of the supplemental bars 8 and 9 are passed two clamping-bolts 10 and 11, which are passed also through the slots 7 of the bar 5. When the bars 8 and 9 are moved longitudinally away from each other, the clamping-bolts travel in the slots 7, and when said supplemental bars have been properly adjusted upon the main bar 5 the clamping-bolts are tightened and hold them against further movement. By the use of two clamping-bolts pivotal displacement of the supplemental bars is prevented. The feet 12 and 13 of the L-shaped bars project at the same side as the main bar and are so offset that they lie in the same plane with the main bar, and pivoted to the free end portion of each foot is a block, (shown at 14 and 15, respectively.) Each of the blocks is capable of an angular movement of approximately two hundred and forty degrees, 60 the free end of each block passing in its angular movement beyond the free end of the foot to which it is connected. In the free end portion of each of the blocks 14 and 15 are formed side notches 15' and 16, which align 70 transversely of the block and at the inner ends of which notches or slots are slight enlargements 17 and 18, respectively, which are designed to receive slidably the wires of a fence that are to be passed through the slots thereinto. In each of the blocks 14 and 15 is a longitudinal guide-slot 19, through which is passed a bolt 20, which is engaged with a plate 21, disposed against one face of the block and having parallel laterally-directed terminal fingers 22, that slidably engage the upper and lower edges of the block. When the bolt is loosened, the plate may be slid longitudinally of the block, so that its fingers will cover the slots 15' and 16 and prevent passage of the 80 wires therefrom. The handle 6 projects at the opposite side of the main bar from the grip portion and lies between the feet 12 and 13, where it is provided with a pivoted block 23, having the same form and equipment as the 85 blocks 14 and 15.

In the building of a fence with the present machine or tool posts 30 are set in the usual manner, and pairs of wires 31 are attached to an end post, the wires at their opposite ends 90

being connected to a drag 32, so that they are held yieldably, but with a certain degree of tension. A pair of wires is engaged in the slots of each of the blocks, and the machine 5 or tool is permitted to hang with the blocks extending upwardly from their points of support. A slat is then passed between the wires of all of the pairs between the machine and the end post, the machine being very close 10 to the post. The machine is then swung outwardly and upwardly in a curved path, so that the several blocks depend from their pivots, this movement of the blocks serving to give to each pair of wires a half-twist. The 15 machine is then drawn slightly rearwardly, a slat is placed between the wires at points between the last twist and the machine, and the machine is then swung to its original position, with the result that a half-twist in the oppo- 20 site direction is given to the wires. This operation is completed until a sufficient number of slats has been incorporated with the wires. It will of course be understood that after the machine is engaged with the wires the retaining-fingers are shifted to their active positions. 25 The provision of the intermediate pivoted block provides for use of the machine with three pairs of wires, it being understood,

however, that the machine may be employed with only two pairs of wires. Furthermore, the adjustable connection of the supplemental bars with the main bar permits of adjustment 35 of the outer pivoted blocks toward and away from the intermediate block to accommodate different spacings of wires.

What is claimed is—

1. A fence-machine comprising a main bar 40 having a handle, a block pivotally connected with the main bar midway of its ends and having slots in its opposite sides designed to receive wires, supplemental bars adjustably connected with the main bar and having laterally-directed terminal feet, and blocks pivoted to said feet and having slots in their 45 opposite edges to receive wires.

2. A fence-machine comprising a main bar having a handle, supplemental bars adjust- 50 ably connected with the main bar, blocks pivoted to the supplemental bars and each having slots in its opposite edges to receive wires, and keepers mounted upon the pivoted blocks and movable into position to cover and un- 55 cover the slots.

In testimony whereof I affix my signature in presence of two witnesses.

J. R. HUTTON.
